JOHN A. CUPLER II

lace is formed, the core serves no substantial function and even if it should be broken, as by forming the same of a strand whose linear extensibility is substantially less than that of the finished lace, the function of the lace would not be impaired. In actual practice, the core has a greater extensibility than the finished lace and the same does not rupture in usage. The fact that the core has such a minimal cross-sectional dimension in comparison to the finished lace permits the lace to have a uniform diameter throughout which is substantially wholly composed of the wound strands and binder. It will also be apparent that where, say for example, three strands of 160 denier polypropylene are used as a core that the cross-sectional area of such core will be negligible when compared to the cross-sectional area of the finished lace having a diameter of, for example, $\frac{1}{16}$ of an inch.

In actual practice it has been found that nylon is particularly advantageous for use as the wrapping strands while du Pont's Adiprene is the preferred elasto-polymeric binder. Although polypropylene, nylon and Adiprene have been mentioned for use as the core material, winding strands and binder, respectively, it is obvious that many other materials could be used to impart desired characteristics to the shoelace. For example, it has been found that when using Dacron for the winding strands, the wear resistance of the lace is increased although its strength is decreased.

The characteristics of the shoelace may also be altered, as desired, by varying the pitch of the helically wrapped strands. The extensibility of the lace is increased by increasing the number of wound turns per inch while the strength of the lace is decreased and, conversely, the strength is increased and extensibility decreased by decreasing the number of turns per inch.

The winding strands themselves may be inherently linearly extensible or inextensible as desired. Thus when using inextensible winding strands, the extensibility of these strands in relation to the lace will be derived solely from their winding bias and when using linearly extensible strands, their inherent extensibility will supplement that imparted thereto by the winding bias.

The shoelace according to the invention may be manufactured as an endless loop or lace in the manner described in connection with an endless belt in the aforementioned copending application after which time the same may be cut to desired lengths either prior to packaging for sale or by the consumer himself. In one form of the invention, the grit is added to the binder material before it is applied to the lace during the manufacturing process such as by adding the same to the binder in the fountain applicator as disclosed in the aforesaid copending application.

In the case of extensible shoelaces, it is particularly desirable to use wrapping strands which are relatively non-porous and whose surface exhibits a slick or smooth finish. Nylon is representative of strands of this type and these characteristics facilitate the relative movement between the strands and binder.

As will be apparent from the foregoing, it is also within the contemplation of the invention to construct inextensible laces by using an inelastic binder which is tightly bonded to the wrapped strands. In this latter case, where wearability rather than extensibility is the desired objective, a strand material such as Dacron exhibiting a porous dull surface may be used which permits a much stronger bond between the binder and strands to resist relative movement.

DESCRIPTION OF THE DRAWINGS

FIG. 1 is a schematic plan view of an endless lace member prior to the time the same is cut to form individual shoelaces;

FIG. 2 is an individual shoelace cut from the lace member of FIG. 1;

FIG. 3 is a greatly enlarged fragmentary illustration of one end of a shoelace having portions thereof broken away; and

FIG. 4 is a greatly enlarged cross-sectional view taken along the line 4-4 of FIG. 2.

DESCRIPTION OF THE PREFERRED EMBODIMENTS

The completed shoelace 10 shown in FIG. 2 may be initially formed as an endless member 12 in the manner described in detail in the aforementioned copending application with the single exception that a granular abrasive is added to the binder prior to its application in the coating process therein described. After the endless member is formed it may be cut to desired lengths as along the cut lines 14 of FIG. 1 to provide the shoelace herein described having minute core 16 and oppositely helically wound strands 18, 20 embedded in elasto-polymer 22 that is impregnated with a granular abrasive 24. Although three strands 26 have been illustrated as comprising the core 16 it will be apparent that a single strand or a larger number of strands may be used consistent with the requirement that the core be extremely small as compared to the finished lace.

The presence of the granular abrasive provides a roughened outer surface on the finished lace which affords an excellent gripping action between the engaged portions of a knot. This gripping action coupled with the inherent resiliency of the lace which tends to return to its normal unstressed state after release of the stress applied thereto during a knotting operation, provides for a very secure knot that will not tend to slip or become unknotted. Inasmuch as the abrasive is embedded uniformly throughout the binder, any of the abrasive that is worn off in use will expose underlying abrasive particles and the non-slip characteristic of the lace will not be impaired.

If the appearance of a lace tip is desirable for cosmetic purposes, the same may be readily formed on the ends of the monoform lace merely by heating and compressing the end portions thereof. In other instances such treatment of the lace ends may be desirable to render the same relatively rigid although the cut ends of a lace constructed in the manner described wherein the same is merely cut to length exhibits sufficient rigidity that lacing operations are not impaired.

I claim:

1. An untipped lace of substantially uniform diameter comprising; a central core surrounded by at least one sheath of oppositely wound alternately wrapped filamentary strands embedded within a plastic binder for movement relative thereto.

2. The lace of claim 1 wherein said core consists of not more than ten parallel strands.

3. The lace of claim 2 wherein the diameter of each of said strands forming said core does not exceed that of a 160 denier polypropylene strand.

4. The lace of claim 2 wherein said binder is an elasto-polymer.

5. The lace of claim 4 wherein said wound strands are linearly extensible.

6. The lace of claim 5 wherein said binder has a greater coefficient of extensibility than said wound strands.

7. The lace of claim 5 wherein said core has a greater coefficient of extensibility than said binder.

8. The lace of claim 2 wherein said parallel strands are polypropylene.

9. The lace of claim 1 wherein said binder has a relatively retentive surface.

10. The lace of claim 1 wherein the outer surface of said shoelace is roughened.

11. The lace of claim 10 wherein an abrasive grit is embedded in said binder to provide said roughened surface.

12. The lace of claim 11 wherein said grit is embedded substantially uniformly throughout said binder.

13. The lace of claim 1 wherein said alternately wrapped strands in said at least one sheath have diametrically opposite portions extending equidistantly from 5 the axis of said core.

14. An untipped lace of substantially uniform diameter comprising; a central core surrounded by oppositely wound filamentary strands embedded within a plastic binder for movement relative thereto, said core consisting of not more than ten parallel strands, and wherein a bond 10 is formed between said strands and binder that is of lesser strength than the internal bonding strength of said binder whereby under stress conditions portions of the bond be-

tween the binder and strands may be broken to facilitate said relative movement.
